(57) **CLAIM**

The ornamental design for a tiller for outboard motor, as shown and described.

DESCRIPTION

FIG. 1 is a perspective view of a tiller having our new design.

FIG. 2 is a left side view.

FIG. 3 is a right side view.

FIG. 4 is a rear view; and,

FIG. 5 is a top view.

The broken lines represent portions of the tiller that are shown for illustrative purposes only and form no part of the claimed design.
